UNITED STATES PATENT OFFICE.

DAVID C. BETTISON, OF OMAHA, NEBRASKA.

RELAY.

Application filed August 9, 1926. Serial No. 128,287.

My invention relates to electric relays, particularly relays operated by direct current, and of the types used for railway signalling. It is the general object of my invention to provide in relays of this class certain refinements of construction, whereby to facilitate the adjustment of the relay for operation in the desired manner, and whereby the adjustments made will be substantially 5 permanently retained and not be subject to spontaneous or accidental variations. A particular object of my invention is to provide a novel method and means for supporting the relay armature, whereby said supporting means will not be subject to wear, or liability to become inoperative by sticking of parts together by corrosion, or by welding of parts together by fusion, resulting from lightning or other high-tension electrical 10 discharges through the instrument, and whereby adjustments may be made of the polar gap or normal distance at which the armature is held from the pole-pieces of the electromagnets. A further object of my invention is to provide in relays of the class 15 mentioned a novel construction of the contacts whereby said contacts may be readily adjusted to a desired gap when in open position, and to the desired contact-pressure 20 when in closed position, the adjusting means being such that the faces of the stationary contacts may be accurately alined with the faces of the movable contacts, and a plurality 25 of sets of the contacts be alined or adjusted to close and open their respective 30 circuits simultaneously, and whereby said adjustments of the contacts involve no uncontrolled deformations of the parts, such that spontaneous changes of the adjustment 35 may subsequently occur by reason of a tendency of the deformed parts to resume 40 their original formation.

In the accompanying drawings Fig. 1 is a side view, partially broken away, of a relay embodying my invention, Fig. 2 is a 45 diagrammatic view illustrating the movement of the armature from open to closed position about the quasi-fulcrum formed by the flexible armature-supports, Fig. 3 is a 50 partial rear view of armature supports and associated parts, Fig. 4 is a detail vertical section on the line 4-4 of Fig. 1, showing the contacts in front elevation, Fig. 5 is a detail bottom view of one of the adjustable 55 contacts, Fig. 6 is a side view of the same, Fig. 7 is a detail front view of one of the

armature-supporting springs, and Fig. 8 is a sectional view of the same on the line 8-8 of Fig. 7.

In carrying out my invention according to the illustrated embodiment thereof, I provide a relay of which the general construction and operation is substantially that commonly employed for direct-current relays for railway signalling, three being an electromagnet 60 formed by a pair of coils 10 having a connecting yoke 11 at the upper ends of the cores, the lower ends of the cores extending through a base-plate 12 and carrying the pole-pieces 13, beneath which is the movable 65 armature 14. The armature and the contact fingers 15 carried thereby, together with the stationary and movable circuit-controlling contacts and adjusting means, are inclosed by a glass casing 16 which fits within a 70 marginal flange of the base 12, a similarly flanged bottom-plate 17 completing the inclosure, and said bottom-plate being secured to the plate 12 by corner-posts 18. A lateral extension of the yoke 11 carries the 75 binding-posts 19 which form the coil terminals for connection with the external controlling-circuit. Upon the rear portion of the base 12 are mounted the binding-posts 20 from which the flexible conductors 21 are 80 extended to the fingers 15, and upon the front portion of the base are mounted the binding-posts 22 and 23 which carry the front and back stationary contacts respectively. 85

In the usual construction of relays of this class, the armature is supported by pivotally mounting the same between a pair of pivot-pins alined upon an axis about which the armature moves, the latter being swung up 90 toward the pole-pieces when the electro-magnet is sufficiently energized, and dropping away from the pole-pieces by gravity when the energization of the electromagnet is reduced below a determined minimum. In 100 railway signalling mechanism under control of relays it is the invariable practice to have the signals placed at and held in clear position when the electromagnets of the controlling relay attain a certain minimum energization, and to have the signals move to danger position by the opening or closing of circuits effected by the gravitational movement of the relay armature resulting from 105 reduced energization of the electromagnets. Obviously, any defect of the armature support, such as sticking of the pivot-pins by 110

corrosion, or by fusion from lightning discharges, or by excessive friction at the pivots due to bending or other deformations of the pins, may cause the armature to remain in closed position and thus to show a clear signal when the proper indication of the signal should be danger; and in practice it is found that such false signal indications are quite often caused by failure of a relay due to 10 defects of the pivotal supports of the armature such as above mentioned.

The foregoing difficulties and liabilities to failure are avoided in my improved relay, by supporting the armature as follows:

- 15 From the rear portion of the base-plate 12, adjacent to the binding-posts 20, a bracket 24 is extended downwardly as shown, and to the horizontal lower portion of said bracket are secured the lower ends of a pair of 20 flat strips 25 of spring material such as phosphor-bronze. Said spring strips are secured to the bracket by means of small bolts 26 which pass through slots 27 in the strips, the slots permitting a slight vertical 25 adjustment of the strips relative to the bracket. The strips extend substantially vertically, and the upper ends thereof engage the ends of lugs 28 extended rearwardly from the armature 14, and screws 29 are 30 extended through holes 30 in said upper ends of the strips to fixedly secure the same to said lugs 28, and thereby support the armature. The flexible armature-supporting strips 25 are thus disposed in a plane 35 substantially parallel with a plane passing through the axes of the magnet poles, or, with reference to either pole alone, substantially parallel with the line of magnetic traction or the direction in which the magnetic 40 traction is exerted upon the armature; and the strips are spaced laterally from the line of traction sufficiently to enable movement of the armature from and toward the pole-pieces by lateral bending of the strips. During 45 such movements of the armature the lateral deflection of the spring strips is distributed over a considerable portion of their length, being greatest adjoining the fixed lower ends thereof and decreasing toward the upper ends to which the armature is secured, and the resulting movement of the armature is substantially the same that would occur if the strips were rigid and inflexible, and were pivoted to swing about a 50 fixed horizontal axis located near their lower ends. The action above mentioned will be clearly apparent from the diagrammatic representation of the parts in Fig. 2, wherein the circle 31 indicates the hypothetical or quasi-fulcrum about which the pivotal movement occurs, the vertical line 32' indicates the line of traction, and the arrows indicate the paths of movement, respectively, of a point 32 at the center of the armature, and a point 33 at the front end of the rigid ex-

tension of the armature formed by the contact-fingers 15. It will be seen that a point 34 on the rear edge of the armature, at the upper end of the support-strips and directly above the quasi-fulcrum 31, will have substantially no vertical movement but can move only upon an almost horizontal arc, although the movement of the point 32 at the center of the armature has a vertical component substantially equal to the horizontal component, as shown by the arrow and the movement of the point 33, as indicated by the arrow, has a greater vertical and smaller horizontal component. It is noted that, as the point 34 can have no appreciable vertical movement, the amount of upward pressure produced at the point 33 will be proportioned to the magnetic traction at the point 32 inversely as the distances of said points 33 and 32 from the point 34; and that this result cannot be attained by supporting the armature upon flat springs extending transversely to the axis of magnetic traction, because in such case the lateral flexure of the springs would permit movement of the point 34 upwardly when the upward movement of the point 33 was resisted. 90

It will be apparent that by the described flexible armature-supporting means, gravitational movement of the armature to the lowered position thereof, when the pull of the electromagnet falls below the determined minimum, cannot be prevented by sticking, corrosion, fusing or any similar derangement of the armature-supporting means, and that should the springs be broken or destroyed the armature would drop down in such a manner that the controlled signals would be set to danger indication. It will also be seen that adjustment of the air-gap or normal space between the armature and pole-pieces may be effected when desired, by loosening the attaching bolts which pass through the slots 27 in the lower portions of the springs, and tightening said bolts after the 100 desired raising or lowering of the springs has been effected. 105

The contact-fingers 15 are preferably of cast metal, heavy enough to be substantially rigid, and are fixedly secured to the armature and insulated therefrom by the connecting members 35, the rear ends of the fingers being connected with the binding-posts 20 by the flexible conductors 21 as before mentioned. In the illustrated construction, two of the contact-fingers are provided, although any desired number of the fingers may be used, according to the particular use for which the relay is intended, relays of this class being used for various purposes requiring from two to six of the contact-fingers. On each finger a back-contact is formed by a spring 36 secured to the lower side of the finger and adapted to engage the fixed back-contact 37 carried by a loop or 115 120 125 130

stirrup-like member 45 supported by the binding-post 23. A front-contact for each finger is formed by a spring 38 which is preferably a straight flat piece of metal extending diagonally upward and forward from the finger, the latter being formed intermediate its ends with an angular portion 39 so proportioned and arranged that the spring will be held at the desired diagonal position when the lower end portion thereof is secured against the flat side of said angular portion 39. A small bolt 40 is employed for securing both of the springs 36 and 38 to the finger. The contacts 41 which are engageable by the springs 38 are carried by the binding-posts 22, and are adjustably connected therewith as follows: Each contact 41 is secured to the lower portion of a U-shaped strip 42 of resilient metal, and the upper portion or leg of the U-strip is secured by a screw 43 to the lower end of the binding-post which extends through the plate 12. The material used in said strip 42 should be a good electrical conductor, such as brass or bronze, and sufficiently resilient to allow the desired adjustments or variation in position of the contact 41 by spreading or drawing toward each other the ends or legs of the U-strip. The adjustment is effected by means of a pair of screws 44 which pass through openings in one leg and into threaded openings in the other leg of the U-strip adjacent to the open end of the U. By tightening or loosening one of the screws 44 without changing the position of the other, the contact 41 may be slightly tilted laterally whereby to accurately aline the face thereof with the end-face of the respective contact-spring 38. By equal adjustments of both screws 44 the position of the contact 41 may be varied to increase or decrease the gap at open position, to vary the contact-pressure at closed position, and to place a plurality of the contacts in such relation to their respective contact-springs 38 that the controlled circuits will be opened or closed simultaneously.

In relays of the ordinary types, wherein adjustments of the contacts are effected by bending the contact-springs carried by the armature or contact-fingers, the adjustments are not accurately maintained, because of the fact that the set or deformation of the springs, made during the adjustment thereof, tends to be gradually lost by spontaneous return of the spring toward the formation which it had prior to the adjusting deformation thereof. It will be seen that, in my improved construction, adjustments of the contacts made by bending or deformation of the U-strips 42 are definitely and positively maintained by the adjusting-screws 44, and are not subject to variation except by deliberate and intentional re-adjustment of said screws, and that by means

of said adjusting-screws 44 a plurality of the contacts may be easily alined with each other, or adjusted to cooperative relation with the respective contact-springs to produce the desired gap at open position, or the desired contact-pressure at closed position, or tilted laterally to aline the faces of the contacts with the ends of the respective contact-springs. The U-strips 42 form a connection of high electrical conductivity between the contacts 41 and the respective binding-posts 22, and the conductivity of the connection is not altered by adjustments in position of the contacts.

It will be noted also that as the contact-springs 38 are straight flat pieces of metal, the construction thereof will require no deformation of the flat sheets in which the material used in the springs is customarily formed originally, and consequently there will be no tendency for the occurrence of spontaneous variation in the form of said springs 38, whereby the relations of the contacts might be altered after adjustment thereof had been made.

Now, having described my invention, what I claim and desire to secure by Letters Patent is:

1. In a relay of the class described, the combination with an electromagnet and its armature, of means for supporting said armature for movement toward and from the electromagnet, comprising a laterally flexible member secured at one end to the armature and at the other end to a frame-member fixedly associated with the electromagnet, said laterally flexible member extending substantially parallel with but spaced laterally from the line of traction of the electromagnet.

2. In a relay of the class described, the combination with an electromagnet, armature, and frame, of a laterally flexible armature-supporting member extending substantially parallel with but spaced laterally from the line of traction of the electromagnet, one end of said laterally flexible member being secured to the frame and the other end thereof secured to the armature and supporting the same, whereby movements of the armature toward and from the electromagnet are enabled by lateral bending of said armature supporting means.

3. In a structure as set forth in claim 2, means for adjusting the relation of the armature-supporting member to the frame in a direction parallel with the line of magnetic traction, whereby to vary the air-gap between the armature and the poles of the electromagnet.

4. In a relay of the class described, a frame, an electromagnet fixedly mounted thereon and having adjacent poles, an armature positioned in operative relation to said poles, laterally flexible means extending

substantially parallel with the line of traction of said electromagnet and spaced laterally from said axis, said laterally flexible means secured at one end to the frame and secured at the other end to the armature whereby to support the same for movement toward and from the magnet poles and substantially about an axis spaced from said poles and from the axis of attraction.

5. In a relay of the class described, a base-plate, an electromagnet mounted thereon and having pole-pieces projecting beneath the same, a bracket carried by the base-plate and extending downwardly therefrom and spaced from the pole-pieces, flat springs secured to the lower portion of said bracket and extending upwardly therefrom, an armature disposed beneath the pole-pieces and having its rear edge secured to the upper portions of said springs and supported thereon, contact-fingers secured to said armature and extending forwardly therefrom, stationary contacts supported upon the base-plate,

and contact-springs carried by the fingers and engageable with said stationary contacts by movements of the armature toward and from the pole-pieces, said armature movements involving lateral bending of the supporting springs.

6. In a relay of the class described, the combination with a movable armature, and contact-fingers carried by said armature, of a contact-spring carried by each of said fingers, a contact engageable by said spring, and an adjustable support for said contact comprising a resilient U-strip having the contact affixed to one leg thereof and the other leg affixed to a support, and an adjusting-screw for varying the spread of the U-strip at the open end thereof.

7. A structure as set forth in claim 6, including an adjusting-screw for each side of the U-strip, whereby to separately adjust the sides thereof and effect a lateral tilting of the supported contact.

DAVID C. BETTISON.
